(57) **CLAIM**

The ornamental design for footwear upper, as shown and described.

DESCRIPTION

FIG. 1 is a perspective view of the footwear upper embodying the new design;

FIG. 2 is a top plan view thereof;

FIG. 3 is a right side elevational view thereof;

FIG. 4 is a left side elevational view thereof;

FIG. 5 is a front elevational view thereof; and,

FIG. 6 is a rear elevational view thereof.

FIGS. 1–6 show an outsole in broken lines. The outsole is shown for environmental purposes and does not form any part of the claimed design. The texturing shown on the majority of the upper represents a uniform mesh texture and is not merely printed matter.
